CHAIN GRATE.

1,115,904.

Specification of Letters Patent.

Patented Nov. 3, 1914.

Application filed March 9, 1914. Serial No. 823,388.

To all whom it may concern:

Be it known that we, PAUL L. CROWE and AARON FRANKENHEIM, citizens of the United States, residing, respectively, in the 5 borough of Manhattan, city, county, and State of New York, and borough of Bronx, county of Bronx, and State of New York, have invented certain new and useful Improvements in Chain Grates, of which the 10 following is a specification.

Our invention relates to chain grate furnaces, and more particularly to the means of attaching the grate-bars to the chains which flexibly unite the structure, the object 15 being to provide a construction which is simple, strong, effective and easy to put together and take apart.

In the accompanying drawings illustrating the invention: Figure 1 is an elevation of a grate-bar, its intermediate portion being shown broken away for economy of space, and the chains at the ends being indicated in section; Fig. 2 is a side elevation of a portion of the upper course of the grate, 25 one of the grate-bars and the horizontal links being shown in vertical section; Fig. 3 is a plan view of the same; and Fig. 4 is a detail view on an enlarged scale, showing a modification.

It will be understood that these chain 30 grates are endless structures passing around suitable sprockets at front and back, and being driven slowly or intermittently to feed a continuous layer of fuel into and through the combustion chamber of the furnace. In the present instance the grate is 35 composed of transverse grate-bars 1 and endless chains 2 at the ends of the bars. These chains are of the cable chain variety 40 and are disposed with their links alternately horizontal and vertical, assuming the chain to be running horizontally, though as a matter of fact the grate may be disposed at an inclination.

The terms "horizontal" and "vertical" 45 links are used herein for convenience, to designate links which are parallel and perpendicular, respectively, to the plane of the grate.

Each grate-bar comprises a longitudinal 50 web portion 3 and a laterally-projecting fuel-bearing portion 4, of suitable formation. As shown, these fuel-bearing portions are continuous and provided with draft 55 openings, a few of which are indicated; but other constructions will do as well. In the

present instance the term "web portion" is used generally to designate the narrower structural part of the bar which projects downward from the fuel-bearing portion. 60 The exact shape of the grate-bar is not essential.

At one end of the bar, the web 3 is cut away or omitted for a short distance, as at 5, to form a recess to accommodate a vertical 65 link 2^a of one of the chains. To this vertical link the end of the bar is attached by a pin 6 projecting horizontally from the end of the web beneath the overhang of the 70 endwise projecting upper portion of the bar. This pin is preferably a separate piece of metal from the grate-bar, being united therewith by the fact of the metal of the bar being cast around the inner portion of the pin in the process of manufacture. 75 This pin is headless at its outer end and is readily inserted endwise into the opening of the vertical link. At the other end the web is recessed at the bottom, as shown at 7, so that the depth of the web is reduced 80 from the point 8 to the end of the bar. A vertical socket 9 is formed in this reduced portion of the web, for the reception of a removable and replaceable vertical attaching pin 10, the lower end of which is provided with a head 11. In attaching the 85 grate-bar to the chains the said pin is passed upward through the opening in a horizontal link 2^b and between the ends of the two adjacent vertical links 2^a, fitting this opening, 90 and is inserted into the socket 9, where it is held in place by a retaining pin 12, such as a cotter pin, which is passed through transverse registering openings in the attaching pin and the web of the bar, beneath the fuel-supporting portion 4. The head 11 comes beneath the horizontal link, and being too large to pass therethrough reliably secures this end of the bar to the chain. It is to be noted that the head of the pin 10 merges 95 into the shank on a curvature, so that, at front and back, downwardly and outwardly curved surfaces 13 are provided for the reception of the rounded ends of the vertical links 2^a, which are thus enabled to work on the pin in turning around the sprockets (not shown) without necessitating looseness in the connection. The retaining pin 12 performs its function reliably, and is of especial advantage in that the ease of its removal is not seriously affected by rusting or 100 the action of heat on the metal parts. 105 110

Fig. 4 illustrates a modified construction in which the shank of the attaching pin 10^a is curved, and passes movably through a curved socket 9^a, its upper end being 5 transversely apertured at 15 for the reception of a cotter pin.

In the grate as assembled, the bars are arranged alongside of each other with their vertical and horizontal pin ends alternating. That is to say, if in any one grate-bar the vertical pin 10 is at the left end 10 and the horizontal pin 6 at the right, in the two bars at opposite sides of it these conditions will be just reversed. Adjacent ends 15 of adjacent bars engage adjacent links of the corresponding cable chain. Thus, at one side of the grate, the end of one bar engages a horizontal link, the end of the next bar engages the next, vertical link, 20 and so on in alternation; and it follows that the vertical links of one chain are directly opposite the horizontal links of the other chain. By virtue of these relations the bars are held securely to the chains 25 with only a single headed removable fastener apiece, because with the grate once assembled the amount of relative movement, laterally of the grate as a whole, which can take place between the bars and chains 30 is too slight to permit the plain pins 6 to escape from the vertical links.

The subject-matter of this case was in substance disclosed in our prior application Serial No. 400,722, filed November 4, 35 1907, but is not therein claimed, such claims being reserved for this application with benefit of the filing date of the earlier case.

What we claim as new is:

40 1. In a chain grate, the combination with a cable chain comprising horizontal and vertical links, of a transverse grate-bar comprising a longitudinal web portion and a laterally-projecting fuel-bearing portion, 45 said grate-bar having a vertical socket in one end of its web portion, a removable vertical attaching pin inserted upward into said socket through a horizontal link of said chain and having a head on its lower

end beneath said link, and a retaining pin 50 passed through the upper portion of said attaching pin and holding the same in said socket.

2. In a chain grate, the combination with a cable chain comprising horizontal and 55 vertical links, of a transverse grate-bar comprising a longitudinal web portion and a laterally-projecting fuel-bearing portion, said web portion being recessed at the bottom so as to be reduced in depth from a 60 point adjacent one end of the bar to the end thereof and having a vertical socket in said recessed region, a removable vertical attaching pin inserted upward into said socket through a horizontal link of said 65 chain and having a head on its lower end beneath said link, said web portion and attaching pin having registering transverse openings, and a retaining pin passed through said openings beneath said fuel-bearing portion. 70

3. In a chain grate, the combination with two cable chains having their alternate links arranged substantially horizontally and vertically, the horizontal links on one side 75 being opposite the vertical links on the other side and vice-versa, of a series of grate-bars, each having at one end a vertical socket and a removable vertical headed attaching pin therein and at the other end 80 a permanent horizontally-projecting plain pin, said headed pin passing through a horizontal link of one chain with its head beneath said link and said plain pin projecting through the opposite vertical link 85 of the other chain, adjacent bars being reversed as to the positions of said pins, and adjacent vertical and horizontal pins at each side engaging adjacent horizontal and vertical links. 90

In witness whereof we have signed our names in the presence of two subscribing witnesses.

PAUL L. CROWE.
AARON FRANKENHEIM.
